[57] CLAIM

The ornamental design for a toilet light, as shown and described.

DESCRIPTION

FIG. 1 is a right view of the toilet light showing my new design;

FIG. 2 is a left view thereof;

FIG. 3 is a rear elevational view thereof;

FIG. 4 is a front elevational view thereof;

FIG. 5 is a top plan view thereof;

FIG. 6 is a bottom plan view thereof with adhesive tape; and,

FIG. 7 is an isometric view thereof;

FIG. 8 is a reduced perspective view thereof, with the broken line showing for illustrative purposes only and forming no part of the claimed design; and,

FIG. 9 is a perspective view thereof.
